SUSPENSION CEILING

Albert F. Jantsch, Buffalo, N. Y., assignor to National Gypsum Company, Buffalo, N. Y.

Application June 25, 1953, Serial No. 364,022

2 Claims. (Cl. 189—88)

This invention relates to improvements in ceiling and wall constructions and more particularly is directed to improved means for lining ceilings and walls to improve their acoustical qualities, or to provide a desirable interior finish, or the like, as for example where it is impossible, non-feasible, or undesirable to apply the lining directly to the walls or ceiling.

It is a primary object of the invention to provide in a ceiling and wall construction of the aforesaid type, improved means for supporting a lining in spaced relation from its supporting structure.

It is another object of the invention to provide improved furring runner means and improved wire clip fastener means therefor adapted to securely engage said furring runner means in contact with a suitable supporting structure by simply engaging said furring runner means with one end of said clip and snapping its opposite end over a member of said supporting structure without intermovement between the interconnected members.

Still another object of the invention is to provide the aforesaid furring runner means with suitable tile supporting flanges permitting said runner means to be relatively cheaply and easily manufactured.

Still another object of the invention is to provide a universal wire clip of the aforesaid type which is adapted for both right-hand and left-hand use.

Still another object of the invention is to provide tiles which are adapted to be supported, or held in place in improved manner by engagement of their edges by the aforesaid furring runner flanges.

Still another object of the invention is to provide a ceiling construction embodying the aforesaid advantages and having wall abutment support means therefor which provide a neat finish border in addition to being support means.

And still another object of the invention is to provide a ceiling structure of the aforesaid type which is rigid and easily and rapidly installed and having conjoining tile sections in substantially airtight sealing relation so as to eliminate undesirable flow of air, or "breathing" between the room space and the space above the ceiling with changes of temperature and atmospheric pressure.

Still another object of the invention is to provide, in a construction of the aforesaid type, means for replacing tiles without dismantling the surrounding structure.

Still another object of the invention is to provide a construction of the aforesaid type which is readily adaptable in improved manner for stepped wall or ceiling portions, and to accommodate light troffers, or the like.

Further objects and advantages will be apparent in view of the following description.

In the drawing:

Fig. 1 is a fragmentary perspective view as seen from above showing one particular embodiment of the invention;

Fig. 1a is an enlarged fragmentary perspective view

Fig. 14c is an end view of the tile of Fig. 14b in its mounting position between a pair of "runners";

Fig. 14d is a top plan view of the title of Fig. 14c; Fig. 15 is an enlarged fragmentary perspective view showing a method of engaging the aforesaid half-splines in assembled position; and

Fig. 16 is a reduced perspective view of a modification of the aforesaid embodiment of the invention; the modification being a stepped suspension ceiling.

The particular embodiment of the invention illustrated in the drawing generally comprises a suspended ceiling structure including a plurality of "runner" supporting channels 20 hung at a common level in equally spaced and approximately parallel relation, for example to span the underside of a concrete upper floor 21 by means of wire suspension means 22 which are wrapped around said channels and hang from a plurality of wire support loops 23 embedded in the ceiling as shown in Fig. 1. It is obvious that the channels are readily adjusted to a common level by simply twisting the wire suspension means by a toggle rod 24 and that various other methods of fastening the "runner" supporting structure may be devised as is commonly known in the art.

A plurality of furring "runners" 25 (Figs. 1 and 2) are arranged in this particular embodiment of the invention to traverse the aforesaid channel members and to be supported thereby in contacting relation by means of a plurality of wire clips 26. The furring "runners" 25 are each made into generally inverted J channel form, preferably by a rolling operation, or the like, from a suitable sheet of metal such as 25 gage galvanized steel.

More particularly, the furring "runners" are each shaped into a cross-sectional form (Figs. 2 and 3b) comprising a web portion 27 which is bent at its upper edge into a clip retaining hook portion 28 and at its lower edge into a portion bent laterally outwardly and then folded back on itself to provide a tile support flange bead or fin 29 at one side and protruding at the opposite side into a tile support flange 30 having a marginal portion 31 as indicated by "A" in Fig. 3b which is acutely upwardly bent along a line parallel to the web portion 27 and slightly inwardly of the outer edge of the hook portion 28 and having an outer edge which lies in a plane containing the upper face of the bead or fin 29. Thus, the flange portion 30 provides a comparatively resilient supporting surface and is adapted to snugly engage in inwardly and upwardly bearing relation a splice connection channel member 32 inserted into the "runner" end to nest against the web and hook portions of the "runner" in the manner shown in Fig. 3b.

The aforesaid "runners" are made of substantial length, convenient for shipment and installation. They may be shortened by cutting to fit a room of small dimensions, or assembled in line with other "runners" in a large room, and spliced together by the channel splice connectors 32 inserted into abutting ends in the above manner and held in place thereby.

The aforesaid clips 26 of the invention are made, as illustrated in the drawing, from continuous pieces of heavy iron wire bent into any desired form. The preferred form of the clip of the invention is illustrated in Figs. 6, 8 and 9 as comprising a central portion 33 slanted from the vertical and obtusely bent near its lower end as at 34 (Fig. 9) and then being bent upwardly at the bottom into a hook portion 35 which ends in a substantially laterally extending portion 36 which folds back on itself into a "runner" engaging portion 37, the central portion 33 being laterally bent outwardly into a channel-engaging portion 38 at its upper end in the direction of the portions 36 and 37 and being substantially parallel thereto and having a detent 39 at the end thereof a suitable distance from the central portion to overlap and lock said clip in engaged position over the suspension means, as for example the aforesaid channel members 20.

Thus, it is a particular feature of the invention that

the aforesaid furring "runners" are adapted to be easily and rapidly fixed to traverse, for example, the underside of the aforesaid suspension channels in adjustably fixed relation thereto by simply nesting the aforesaid "runner" engaging portion 37 of a clip of the invention into the aforesaid "runner" clip retaining hook portion 28 at the juncture of said "runners" and said channels and then sliding, or rotating, the clip portion 38 to cam it by means of its detent 39 to spring and finally lock over said channels so that it then holds the furring "runner" forcibly against the channel bar. It is, of course, to be understood that when the aforesaid clip is in unstressed position, the distance from the underside of the upper channel-engaging portion 38 to the upper side of the "runner" engaging portion 37 will be somewhat smaller than the combined depth of the channel member 20 and the thickness of the "runner" hook portion 28, whereby the clip must be flexed and strained (but only within its elastic limit) in being applied.

It is also a particular feature of the foresaid preferred form of clip of the invention that multiple spring forces created in its stressed "runner" supporting position provide resultant forces acting normally to the contacting surface between the channels and the "runner," whereby an improved holding action is achieved. A further feature of the clip 26 is its adaptability for either right or left-hand use in embodiments of the invention of the aforesaid type as hereinafter more particularly noted.

A slight modification of the aforesaid furring "runner" clip is illustrated at 40 in Figs. 6a and 6b to comprise a vertical portion 41 having at its upper end a laterally extending portion 42 which is bent to have a detent 43 and having at its lower end a hook portion 44 which ends in a rectangular spiral hook portion 45, the aforesaid hook portions being formed at right angles to each other and so that the hook portion 44 lies in a plane which is perpendicular to the plane containing the vertical portion 41 and the upper laterally extending portion 42. The hook portion 44 is preferably offset in a further modification of the clip 40 illustrated in Fig. 6c as indicated at 46 so that a plane containing the vertical portion 41 and the upper laterally extending portion 42 is substantially equidistant from the sides of the spiral hook portion 45. The hook portion 44 is of course formed of sufficient depth so as to permit the spiral hook portion 45 to nest in and bear against the "runner" hook portion 28 when in assembled position.

As illustrated in Fig. 1, a plurality of titles 47 are adapted to be carried in end-to-end relation between pairs of the aforesaid furring "runners." The tiles 47 in the particular embodiment illustrated (Figs. 1a, 1b, and 1c) are preferably kerfed in all ends as indicated at 48, rabbeted on all four upper edges as indicated at 49, chamfered on all lower corners as indicated at 50, and grooved when desired as at 51 (Fig. 1b) to achieve a decorative effect.

The term "tiles" is used hereinabove, and hereinafter, in a generic sense to include not only ceramic tiles (which may be mounted and set by means of this invention), but also slabs or boards of other materials, and including acoustical tiles, so called, of a material and construction which are largely absorptive of sound vibrations.

It is noted that, for convenience, those sides of the aforesaid tiles which extend along the furring "runners" will be designated as their longitudinal sides, and those sides which extend across from one "runner" to the next, as transverse sides, this regardless of the relative lengths of those sides.

Thus, the tiles are engaged at their longitudinal sides by means of the furring "runner" flanges which are arranged to project into the longitudinal kerfs on each side of the tiles, respectively, and to maintain them at a common level throughout.

A plurality of transverse spline members 52 are preferably stamped, or the like, into straight flat strips of

sheet metal having a centrally embossed area 53. The splines 52 are dimensioned to be adapted for insertion into the transverse kerfs of the abutting tiles 47 to provide transverse support and rigidity therefor and to overlap the "runner" flange portion 30 at one of its ends and to abut the "runner" flange bead 29 at its other end. It is to be understood that, as illustrated in Figs. 8 and 9, in assembled relation, the weight of the tile members will bow the aforesaid "runner" flange marginal portion 31 by a concentration of force as at the point 54 where the splines 52 overlap so that the abutting tiles thereat will be supported in a common horizontal plane. It is also to be understood that a transverse spline member 52a of the type illustrated in Fig. 5 may be used in place of the aforesaid transverse spline 52 when greater rigidity is required.

Another feature of the invention lies in the provision of a plurality of tile bearing spring clips of the type particularly illustrated at 55 (Fig. 7d) for the purpose of applying downward spring pressure from above the aforesaid point 54 to insure bowing thereat of the "runner" flanges, as for example to apply sufficient pressure at the aforesaid point 54 to insure bowing thereof of the "runner" flange as aforesaid (Figs. 1, 8 and 9), or to bear the outermost tiles against the support edge of the hereinabove described wall finish channels to facilitate a substantially airtight ceiling construction, or to permit working upwardly on the aforesaid ceiling to plaster a finish coat, or the like, when desired.

The spring clips 55, as illustrated in Fig. 7d, are preferably formed from spring steel of suitable strength and elasticity into a central runner clamping portion 56 including a pair of inwardly tapered walls 57-57 having suitable inwardly projecting detents 58 therein and a pair of outwardly and downwardly flaring spring arms 59-59 preferably ending in radiused tile pressing edges 60-60. Thus, the spring clips are adapted to be pressed over the aforesaid furring "runner" hook portions to press against the upper face of the aforesaid tiles, being retained in tile-pressing engagement by locking of said detents against the edge of the "runner" hook portion 28. It will be understood that the detents 58 may be arranged in spaced relation, as shown in Fig. 7d, so as to be adaptable for use with tiles of varied thicknesses in a construction of the aforesaid type. It will further be understood that the distance from the detents 58 to the tile engaging edges 60-60 of the aforesaid spring clips when in unstressed condition will be substantially larger than the distance from the detent engaging edge of the "runner" hook portion 28 to the upper face of the tiles when in assembled relation therewith and the spring clip wall-to-wall spacing shall be substantially smaller at their lower portions than the width of the "runner" hook portion whereby the clip must be flexed and strained substantially outwardly and upwardly in being applied, whereupon it then forces the tiles firmly downwardly to a common level.

Thus, the aforesaid construction employs an arrangement of tiles, furring "runners," splines and clips providing joints between abutting tiles which are substantially airtight so as to prevent the flow of air, or "breathing," as it is called, between the room and the space above the ceiling with changes of temperature and atmospheric pressure. Such air flow, although inconsiderable, leaves a deposit of dirt around the openings through which it passes, and in time causes the spots so affected to appear soiled in contrast with the rest of the tile surfaces. Such breathing and discoloration is prevented throughout the entire extent of the joints between contiguous tiles. Throughout the major part of these joints it is prevented by the flanges of the furring runners and spline edges extending deeply into the end kerfs or grooves of the tiles. The deep penetration of such flanges and spline edges makes the only course through which air can flow a long and tortuous one, while their engagement with either top or bottom groove-bounding ledges of the tiles, substan-

tially blocks these tortuous passages. The overlap of the splines as aforesaid on one of the furring "runner" flanges also helps to eliminate breather openings and to provide a rigid ceiling structure.

Still another feature of the invention lies in the particular arrangements utilized for providing wall support and a finish border for a suspension ceiling of the aforesaid type. Thus, as illustrated in Fig. 7, finish wall channels as indicated generally at 61 are fixed to the side walls 10 62 as for example by nailing, or the like. The finish channels 61 are preferably stamped, or the like, from a suitable sheet material into a wall-abutting web portion 63, an upper flange portion 64, and a lower finish-border and support flange 65 preferably having an upwardly turned 15 marginal edge portion 66 having a tile bearing edge 67. The bottom face of the flange 65 is preferably prefinished as by enameling, or the like, so that after installation thereof, a finished ceiling border will be provided without requiring any time-consuming decorative border trimming efforts. It will be understood that the distance between the tile bearing edge 67 and the underside of the 20 upper flange portion 64 will be slightly greater than the distance from the lower face of the tiles to the top of the supporting "runners" so that in assembled relation at 25 opposite walls of a room the "runners" will abut the finish channel web portions at points under the upper flange portion while the outer marginal end portion of the tiles will rest on the tile support edge. Of course, along walls substantially parallel to the "runners," the tile support edges of the finish wall channels fixed thereto will 30 provide end support for the outer marginal edges of the outermost rows of tiles.

The aforesaid finish channels are made in substantial length, convenient for shipment and installation. They 35 may be shortened by cutting to fit a room of small dimensions, or assembled in line with other finished channels in a large room, and spliced together by means of a channel splice connector 68 (Fig. 7b) inserted into abutting ends thereof in the manner indicated in Fig. 7c. Thus, a construction of the aforesaid type is obviously adapted for 40 storage and shipment in compact and space-saving form and is easily installed without special tools or skilled labor.

It is noted that a plurality of spring spacers as indicated at 69 (Fig. 7) are positioned between the aforesaid 45 finish channel web portions and the ends of the tiles to hold the tiles of each row between a pair of furring "runners" in firm engagement with each other to insure the aforesaid anti-air breathing characteristic of the present construction.

50 The spring spacers 69 as illustrated in Fig. 7a are preferably formed from flat spring steel having suitable strength and elasticity into a tile pressing face 70 having angularly outwardly extending spring arms 71-71 which end in finish channel web contacting flanges 72-72. It 55 will, of course, be understood that when the spacer is in unstressed position, the distance between the flange 72 and the face 70 shall be greater than the end clearance between the tile ends and the finish channel web portion 60 whereby the clip will be flexed and strained (but only within its elastic limit) when applied.

A method of suspending a ceiling of the aforesaid type by means of the hereinabove described elements is as follows. The channel bars 20 having been suspended and leveled, "runners" are fastened up against them from beneath by the clips 26 and spaced apart approximately equal to the width of the tiles. Preferably they are arranged symmetrically with respect to the room; that is, with the middle two runners equidistant, on opposite sides, from the middle line of the room, so that if the 70 dimension of the room is not equal to a whole number of tiles, the tiles may be cut so that the two outermost rows will have the same width. The finish channels 61 are fixed to the walls with their upper flanges resting on the ends of the "runners" where they abut the channel web 75 portions and continue around the room to be fixed at a

common level. Tiles are first inserted between the two middle runners beginning ordinarily at one end of the intermediate space with the endmost tile resting on the aforesaid channel edge 67 and being backed in the aforesaid manner by the spring spacer 69. It may be preferable to fasten furring "runners" to the suspension means and insert tiles therebetween in that order for ease in assembly, splicing the said furring "runners" in proceeding from wall to wall. Transverse splines are inserted between successive tiles of the row. Other rows are similarly set on each side of the middle row until the walls of the room are reached. If necessary in order to bring the tiles of adjacent rows close together, the "runners" may be moved laterally without disconnecting their holding clips from the bars of the suspension structure, as by exertion of a moderate thrust or taps of a hammer. In the outermost rows adjacent the room walls tiles are preferably inserted between the "runner" and the finish channel beginning from both ends and working toward some intermediate point so that the last tile in an outermost row will be pressed against the spring spacer pressure toward the channel web portion simultaneously with displacement of the adjacent tiles against the tile row end spacers, whereby said last tile may then be snapped into position.

Figs. 10 and 12 show a plan view of an arrangement of the aforesaid embodiment of the invention for accommodating in improved manner a plurality of lighting units comprising trough-like units, as indicated at 73, containing illuminating devices such, for example, as the so-called "fluorescent" units.

Thus, for example, as shown in Figs. 11 and 13 the suspension channel members 20 and the furring "runners" 25 are arranged to provide openings of suitable size to accommodate the light troffers therebetween. The tiles are installed in the hereinabove described manner around the aforesaid light troffer openings. The light troffers are made of sheet metal having flanges 74-74 which can be relatively displaced against the elasticity of the light troffer body. Thus, one flange 74 of the light troffer is preferably inserted into the transverse kerfs of the tile ends facing one side of the light troffer opening below the flanges of the furring "runners" as indicated at 75 (Figs. 11 and 12) and an opposite flange 74 is then elastically flexed to clear the opposite side of the said opening and then is snapped into the transverse kerfs of the tile ends facing said opposite side, whereby said light troffers are then neatly supported in the aforesaid construction.

It is another feature of the invention that the aforesaid clips 26, as seen in Figs. 11 and 13, provide minimum clip projection into the aforesaid light troffer openings, thereby eliminating possible interference therewith during installation of the hereinabove described light troffers in the hereinabove described manner.

Furthermore, still another feature of the invention particularly embodied herein, as illustrated in Figs. 14, 14a, 14b, 14c, 14d and 15 lies in providing means for replacing individual tiles in the aforesaid ceiling assembly without dismantling the surrounding structure. Thus, an old tile may be simply broken as shown in Fig. 14 and removed. Then, a special replacement tile 76 (Fig. 14b) is made from a standard tile section 47 by cutting back approximately one-half of the upper rabbeted wall of the transverse kerfs as shown at 77-77 from one end of each thereof and then cutting off the entire longitudinal upper kerf wall across the opposite end as at 78. A pair of shortened replacement spline members 79-79 (Fig. 14a) are inserted in the transverse kerfs at one end of the tiles adjacent the ceiling opening. Then, the tile 76 is fitted on the "runner" flange at one end thereof and then swung from the solid line position into the dotted line position thereof shown in Fig. 14c and seen in plan view in Fig. 14d. Then, the splines are merely shifted as shown in Fig. 15 into engagement

with the replacement tile section 76 whereby a three point suspension is provided therefor.

Application of the invention to form upright walls, or an inner lining or facing for walls, is made in essentially the same way as hereinabove described except that the channels or bars 20 are set to conform with a wall instead of a ceiling. They may be thus set vertically side by side, or horizontally one above another. They may be placed alongside an already complete wall, spaced apart from it far enough to admit the clips 26, or serve as the skeleton of a wall. The furring "runners" are attached to them by the aforesaid clips, to run horizontally if the bars are vertical, or vertically if the bars are horizontal, or may be inclined if necessary. With such variation in direction, the wall construction is substantially identical with the illustrations in the drawing and the foregoing description, and the mode of laying the tiles proceeds in essentially the same way. With this explanation, it will be understood that the term "runner," and the terms indicating direction and position with respect to the horizontal and vertical, used in the foregoing detailed description, have no significance as limiting the scope of the protection which is hereinafter claimed, but are merely convenient terms of description.

Thus, the hereinabove particular embodiment of the invention is readily adapted for construction of various types of ceilings and walls as for example, the stepped ceiling construction illustrated in Fig. 16, the details of which will be apparent to those skilled in the art in view of the hereinabove description.

This invention, in all its illustrative embodiments, provides a very flexible, and yet absolutely secure, support for the facing tiles, which enables them to be set flush with one another and with complete concealment of the holding means. Although this illustration shows the tiles as beveled on the edges, this is not an essential feature and they may be made with square edges and set with very inconspicuous joints. At the same time the whole structure may be assembled, and the tiles set in place, with great ease and rapidity. The ceiling or wall facing so made may be of a sound deadening character or not, as desired, according to the nature of the tiles selected, and it may be plain or have any desired quality of ornamentation which may be imparted to each tile individually before assembly or to the ceiling after assembly. Square or rectangular outline of the tiles is not obligatory, since they may have any other polygonal forms which will match together, and the furring "runners" need not necessarily be parallel to one another, although generally it is preferable that they should be. A very low cost of installation is possible with this invention.

Although only illustrative structure has been shown and described in detail, it will be understood that the invention is not so limited but that various changes can be made therein without departing from the spirit of the invention and scope of the appended claims.

What is claimed is:

1. The combination consisting of a horizontal elongate suspension member, a substantially perpendicularly disposed, horizontal, elongate ceiling-tile-supporting runner mounted adjacent therebelow and a wire clip attached to said suspension member and said runner, said runner comprising an elongate, vertical central web, means on the lower end for supporting ceiling-tile edges, and an upper hanger portion of downwardly opening, elongate, channel form, said channel being wider than the diameter of the wire of said wire clip, said clip comprising a single generally vertical leg, means on said upper end of said clip overhanging said suspension member, said clip bottom end having a runner hanger engaging hook resiliently urging said runner against said suspension member, said hook including an engaging portion extending parallel to said runner disposed within the channel of said hanger portion.

and disposed at least in part vertically below said suspension member, said engaging portion having a greater dimension in a direction parallel to said channel and being in the form of a spring having a transverse compressibility and having a normal unsprung effective width relative to the width of said channel such that said engaging portion is frictionally held by said channel in fixed position relative to said channel, said engaging portion comprising essentially a plurality of sections formed by bends in said engaging portion, said sections having a general extent parallel to and within said channel and each said section resiliently frictionally engaging a respective opposite wall of said channel, providing a stable complementary fit of said engaging portion within said channel whereby a completely stabilized attachment of all elements of said combination is provided by said single-legged clip.

2. The combination consisting of a horizontal elongate suspension member, a substantially perpendicularly disposed, horizontal, elongate, ceiling-tile-supporting runner mounted adjacent therebelow and a wire clip attached to said suspension member and said runner, said runner comprising an elongate, vertical central web, means on the lower end for supporting ceiling-tile edges, and an upper hanger portion of downwardly opening elongate channel form, said clip comprising a single generally vertical leg, means on said upper end of said clip overhanging said suspension member, said clip bottom end having a runner hanger engaging hook resiliently urging said runner against said suspension member, said hook including an engaging portion extending parallel to said runner disposed within the channel of said hanger portion, and disposed at least in part vertically below said suspension member, said engaging portion having a greater dimension in a direction parallel to said channel and being in the form of a spring

having a transverse compressibility and having a normal unsprung effective width relative to the width of said channel such that said engaging portion is frictionally held by said channel in fixed position relative to said channel, said engaging portion comprising essentially two parallel channel engaging legs formed by a reverse bend therebetween, said channel engaging legs extending parallel to and within said channel and each said channel engaging leg resiliently frictionally engaging a respective opposite wall of said channel, providing a stable complementary fit of said engaging portion within said channel, whereby a completely stabilized attachment of all elements of said combination is provided by said single-legged clip.

UNITED STATES PATENT OFFICE
CERTIFICATE OF CORRECTION

Patent No. 2,877,878

March 17, 1959

Albert F. Jantsch

It is hereby certified that error appears in the printed specification of the above numbered patent requiring correction and that the said Letters Patent should read as corrected below.

Column 4, line 13, for "poistion" read -- position --; line 20, for "foresaid" read -- aforesaid --; column 5, line 21, for 'aforesaid point 54 to insure bowing thereat of the "runner"' read -- said tiles to keep the tiles resting firmly on the "runner" --; column 7, line 35, for "the installed" read -- then installed --.

Signed and sealed this 30th day of June 1959.

(SEAL)
